United States Patent Office

Des. 187,435
Patented Mar. 15, 1960

187,435

BOTTLE

John Frederick Becker, Vineland, N.J., assignor to American Home Products Corporation, New York,
N.Y., a corporation of Delaware

Application October 12, 1959, Serial No. 57,913

Term of patent 7 years

(Cl. D58—9)

Fig. 1

Fig. 2

Fig. 1 is a front elevational view of a bottle, showing my new design;

Fig. 2 is a side elevational view thereof.

The rear of the animal-like portion of the bottle is substantially plain except for the tail which is S-shaped in its vertical direction.

I claim:

The ornamental design for a bottle, as shown and described.
